UNITED STATES PATENT OFFICE.

HENRY P. ROBERTS, OF JAMESTOWN, NEW YORK, ASSIGNOR OF ONE-HALF
TO FRANK W. ADAMS, OF SAME PLACE.

LEATHER-SKIVING MACHINE.

SPECIFICATION forming part of Letters Patent No. 235,172, dated December 7, 1880.

Application filed September 16, 1880. (No model.)

To all whom it may concern:

Be it known that I, HENRY P. ROBERTS, of Jamestown, in the county of Chautauqua and State of New York, have invented an Improvement in Leather-Skiving Machines, of which the following is a specification.

The nature of this invention relates to certain new and useful improvements in that class of machines employed for splitting or 10 skiving leather; and the invention consists in the peculiar construction, arrangement, and combination of the various parts, all as more fully hereinafter set forth.

Figure 1 is a front elevation. Fig. 2 is a 15 side elevation. Figs. 3 and 4 are details of construction.

In the accompanying drawings, which form a part of this specification, A represents a suitable stand or frame for supporting the operating parts of the device.

B B represent two standards rising from the top of the frame A, and between these standards are suitably journaled the metallic rollers C C', operated by a crank-handle, D, 25 in the usual manner. The roller C' is journaled in boxes a, which have a vertical sliding movement in the standards, and the boxes rest upon the inner ends of the cam-levers D', pivoted to said frames. The outer ends of 30 these levers D' are connected to a treadle-lever, E, by the rod P, the whole being so arranged that the roller C' may be raised or lowered to or from the roller C, so as to exert a greater or lesser pressure upon the leather 35 to be operated upon.

F represents a knife, which is secured to the offset b of the standards, and G is a spring-plate secured to the offset c of the standards, the inner edges of the plate G and knife F being so adjusted as to form a throat, d. Above 40 the knife is a roller, H, suitably journaled in

a frame, I, which latter is properly secured in guides J, which have a vertical sliding movement in the standards B. A small stud, e, rises from the top of the guides J, and to 45 these studs are pivotally secured the outer ends of the levers K. These levers are fulcrumed at h in the head L, which spans the top of the standards, and secures them rigidly together. The inner ends of the levers K are 50 pivotally secured to the swivel-head M upon the lower end of the screw N, threaded through the head L, and which carries a hand-wheel, O.

In practice the roller H may be raised or depressed by rotating the screw N, which, 55 through the connections hereinbefore described, causes the guides to slide up or down in the standards, and thus adjust the roller to the desired relative position with the knife, so that the latter will cut a thicker or thinner 60 quantity from the leather presented to it, while the spring-plate G holds up the advancing portion of the leather and prevents the knife from cutting too deeply or uneven. After the leather has been cut it is presented to the 65 rollers C C', which are brought together, so as to firmly squeeze the leather as it passes between them.

What I claim as my invention is—

The combination, with the stationary knife 70 F and spring-plate G, of the swinging roller H, journaled in the frame I, guides J, carrying the frame I, levers K, pivoted to the guides and head, head L, screw N, and swivel-head M, secured to the lower end of the screw 75 and pivotally secured to the inner ends of the levers K, substantially as described, and for the purpose set forth.

HENRY P. ROBERTS.
